MORTISING MACHINE

Judson H. Mansfield, Rockford, Ill., assignor to
Greenlee Bros. & Co., Rockford, Ill., a corpora-
tion of Illinois

Application November 29, 1940, Serial No. 367,818

8 Claims. (Cl. 144—78)

This invention relates to mortising machines of the type in which a hollow chisel member is supplemented by one or more auger bits rotatably mounted in the chisel for performing a substantial part of the removal of material in the mortising operation.

One object of the invention is to provide an improved mortising head and tool for a machine of this character in which a plurality of auger bits are rotatably associated with the chisel member.

Another object of the invention is to provide a driving train for a plurality of auger bits thus associated with a chisel member, said train being arranged to permit the auger bits to operate very close to each other upon parallel axes.

A further object is to provide for individual endwise adjustment of the bits in relation to the chisel member to compensate for wear and for grinding back of the cutting edges of the chisel when it is sharpened.

It is also an object of the invention to provide an auger bit for use within the chisel of a mortising machine and having provision for feeding out the chips, but specially formed to prevent the chips from packing at the upper end of the grooved portion of the bit.

More specifically, it is an object of the invention to provide an auger bit for rotation within a bore of the chisel of a mortising machine, said bit having a helical groove for conveying the chips upwardly from the cutting end to a point of discharge, and having an oppositely helical groove in its upper portion for preventing the chips from packing around the upper end of the bit and in the bore of the chisel.

Other objects and advantages will appear from the following description taken in connection with the accompanying drawings in which:

Figure 1 is a side elevation of a mortising machine of the type to which this invention applies.

Figure 2 is a front elevation partly in section, showing the tool head and mortising chisel, section being taken substantially at the plane of the axes of the auger bits and their drive shafts.

Figure 3 is a vertical section taken principally as indicated at line 3—3 on Figure 2.

Figure 4 is a horizontal detail section taken as indicated at line 4—4 on Figure 3.

Figure 5 is a detail section taken as indicated at line 5—5 on Figure 3.

Figure 6 is a top-plan view of the head shown in Figures 2 and 3, as indicated at line 6—6 on Figure 3.

Figure 7 is an enlarged vertical section at the

same plane as Figure 3, showing one of the auger bits and adjacent portions of the chisel member.

Figure 8 is a transverse section taken as indicated at line 8—8 on Figure 2.

Although I have shown in the drawings, and shall herein describe in detail, a single form of the invention, I do not intend to limit the invention to the particular form shown, but aim to cover all modifications and alternative constructions coming within the scope of the claims.

The mortising machine illustrated generally in Figure 1 includes an upright frame 1, having a work supporting table 2 and a head 3 slidably mounted in the frame for movement toward and from the table. By means of suitable linkage, not shown, housed within the frame 1, a treadle 4 is arranged to control this vertical movement of the head 3 for feeding the chisel member 5 into the work piece, indicated at 6, to form a mortise therein. It may be understood that the mortising tool is of the type which includes one or more auger bits rotatably carried within the tool for removing a substantial portion of the material in the process of forming a mortise. These bits are driven by means of a suitable electric motor enclosed within a housing 7 which surmounts the head 3, and is connected to move with it throughout its range of vertical adjustment in the frame 1.

The head 3 is shown on a larger scale in Figures 2 and 3, which include also the chisel 5 of rectangular cross-section, having its upper end portion fitted into and securely clamped in the head by means of clamping nuts 8 which bear against a separable portion 9 at the lower end of the head 3. The chisel member 5 is provided with a plurality of auger bits 10 which, in the particular tool illustrated, are four in number and are rotatably mounted within parallel bores 11 in the body of the chisel member 5.

Each of the auger bits includes a pointed center 12 and a single spur or cutter 13 at its lower end, and the end portion 14 which carries the center 12 and cutter 13 is of slightly larger diameter than the bore 11 and is tapered back to its connection with the helically grooved body portion of the bit in which a helical groove 15 is formed for conveying the chips upwardly from the cutting end. The lower end of the bore 11 is slightly flared at 16 to accommodate the tapered end portion 14 of the bit, but suitable running clearance is provided between these tapered parts and also between the main body of the bit and the bore 11.

A slot 17 is formed in the front wall of the

chisel member 5 opposite each of the bores 11, and similar slots 18 are formed in the back wall, also registering with the respective bores 11 so that as the auger bits 10 rotate, the chips carried upward by the helical conveyor grooves 15 may be discharged from the interior of the chisel. Preferably, to avoid unduly weakening the chisel body through too great a portion of its length, the openings 17 and 18 are vertically offset with respect to each other, the openings 18 extending lower in the chisel body than the openings 17, and the openings 17 extending higher than the openings 18, as clearly seen in Figure 7.

But in spite of the provision of the discharge slots 17 and 18 there is a tendency for some of the chips to continue upwardly in response to the conveyor feed of the groove 15, and eventually this material might pack and clog the upper end portion of the helical groove or the cylindrical shank 19 of the bit so as to seriously impair its operation. To prevent this, an oppositely helical groove 20, which need not consist of more than a single turn, is formed adjoining the groove 15 at the upper end so as to operate as a conveyor, tending to feed downwardly any chips which are carried to this height by the groove 15; and since the opening 17 extends opposite the lower end of the groove 20 where it connects with the groove 15, the chips feeding downward along the groove 20, and thus feeding upward along the groove 15, are easily discharged through the opening 17 as they tend to accumulate at the junction of the two helical passages. Thus it is rendered certain that the chips will not accumulate in the upper end of the chisel member 5, and that they will not interfere with the free running of the auger bits 10.

As seen in Figure 3, the shank of each bit 10 includes a reduced and threaded terminal portion 21 at its upper end, and this part is screwed into the threaded bore 22 of a drive spindle 23 journaled in the head 3 of the machine. Below the threaded portion 22 the end of the spindle is counterbored at 24 and is formed with clutch teeth 25 for engagement with similar teeth 26 on the upper end of a clutch collar 27 mounted in alignment with the spindle shaft 23. The collar 27 is provided with a key or spline 27a which slidably engages in a groove or key slot 28 in the shank 19 of the auger bit 10 for driving it when the collar 27 is positioned with its clutch teeth in engagement with the toothed lower end of the drive spindle 23.

As seen in Figure 2, a separate clutch collar 27 is provided for each of the auger bits 10. These clutch collars are normally held in driving relation to the spindles 23 by means of a slide 29 guided for limited vertical movement in the head 3 upon slide plates 30 which are secured to the front face of the head by screws 31, and extend into engagement with vertical grooves in opposite sides of the slide member 29. This member 29 is bored to accommodate the shanks 19 of the auger bits, and is counterbored at 32 to engage the lower ends of the clutch collars 27. The slide rests upon a rock shaft 33 extending across the head 3, and said shaft is formed with a flat face 34 at one side, so that when the shaft is turned through an angle of 90 degrees by means of its handle 33a it acts as a cam to lower the slide 29 onto the flat face 34, thus lowering the clutch collars 27 out of driving connection with the toothed lower ends of the spindles 23.

With the slide 29 and the clutch collars 27 thus lowered it is possible to rotate each of the auger bits 10 for adjusting it endwise by means

of its threaded connection at 21 with its spindle 23 so as to bring the tapered end portion 14 into correct relation to the flared portion 16 of the bore in the chisel 5 to insure that the auger will run freely in the chisel but without excessive clearance, and with its cutting spur 13 properly related to the lower end of the chisel body 5. It will be understood that the lower edges and corners of the body 5 are sharpened to cut away the portions of the mortise which are not removed by the augers themselves, and that resharpening of these edges will alter their relation to the lower ends of the augers so as to require readjustment of the latter by means of their threaded connections at 21 with the drive spindles 23. When each of the augers has been satisfactorily adjusted its clutch collar 27 is turned a few degrees one way or the other to bring its driving teeth 26 into registration between the teeth 25 of the spindle, and the cam shaft 33 is turned back to the position illustrated in Figure 3 for elevating the slide 29 and thus lifting the clutch collars into driving engagement with the spindles.

It may be understood that each of the auger bits 10 has its cutting spur 13 so positioned as to cut a bore whose diameter is substantially equal to the thickness of the chisel member 5, as measured between its front and back outer faces. And as indicated in Figure 2, the auger bits 10 are mounted in the chisel member 5 with their axes as close together as possible so that the lower end portions 14 of adjacent bits run very close together and their cutters 13 remove a large proportion of the material to be cut away in forming the mortise. In order that the augers 10 and their drive spindles 23 may be grouped so closely a gear train for driving the spindles 23 is arranged as shown in Figure 4. From the housing 7 a drive shaft 35 extends into the head 3, and within a chamber 3a formed within the head 3 said shaft carries a gear 36 meshing with a pair of idler gears 37 journaled within said chamber. Each of the spindles 23 carries a gear 38 meshing with one of the idlers 37; but the faces of the gears 38 are slightly less than half the width of the faces of idlers 37, which permits one gear 38 to mesh with the upper portion of the idler 37 while the adjacent gear 38 meshes with the lower portion of the face of the same idler 37. Thus adjacent spindles 23 are driven in the same direction by the same idler 37, and each of the idlers 37 drives two of the four spindles with which the head 3 is equipped. In other words, both idlers 37 rotate in the same direction and both gears 38 driven by each idler 37 rotate in the same direction; hence, all four of the spindles 23 are driven in the same direction while the staggered arrangement of their drive gears 38 permits their axes to be located very close together and still allows the pinions 38 to be of a substantial size which is adequate to the load to be transmitted, and is also conveniently proportioned for economical production.

Near the upper end each spindle 23 is provided with a flange 40 running between bearings 41 of suitable bearing metal for supporting the spindle vertically in position, and the working thrust against the spindle is arranged to be taken by the ball 42 disposed between the upper end of the spindle and the plug 43, having a beveled upper face 44 which is engaged by the conical end 45 of an adjusting screw 46 by which the position of the thrust bearing may be accurately regulated.

I claim as my invention:

1. In combination, an auger bit having a shank with a cutter at the end of the shank and a helical groove in the shank extending upwardly from the cutter, a second helical groove of opposite pitch connecting with the upper end of the first groove and extending upwardly therefrom in the shank, and means having a bore in which the shank rotates, said bore having a lateral discharge opening opposite the upper portion of the first helical groove.

2. In combination, an auger bit having a shank with a cutter at the end of the shank and a helical groove in the shank extending upwardly from the cutter, a second helical groove of opposite pitch connecting with the upper end of the first groove and extending upwardly therefrom in the shank, and means having a bore enclosing the shank with a lateral delivery opening adjacent the upper portion of the first groove, together with means connected to rotate the bit in a direction for feeding chips upwardly along the shank in the first mentioned groove, the second groove operating to feed chips downwardly and to oppose further upward travel of the chips fed by the first groove.

3. In combination with a mortising chisel an auger bit mounted for rotation within a bore in the chisel, said bit having a shank with a cutter at the end of the shank and a helical groove in the shank extending upwardly from the cutter, and a second helical groove of opposite pitch connecting with the upper end of the first groove and extending upwardly therefrom in the shank, and the chisel having a lateral opening in its said bore extending opposite both helical grooves of the auger.

4. In combination with a mortising chisel an auger bit mounted for rotation within a bore in the chisel, said bit having a shank with a cutter at the end of the shank and a helical groove in the shank extending upwardly from the cutter, and a second helical groove of opposite pitch connecting with the upper end of the first groove and extending upwardly therefrom in the shank, and the chisel having slots in its opposite faces respectively and extending longitudinally adjacent the grooved portion of the auger bit, one of said slots providing an opening opposite the lower portion of the first helical groove and the other

slot extending higher than the first and providing an opening opposite said second helical groove.

5. In combination with a mortising chisel an auger bit mounted for rotation within a bore in the chisel, said chisel having a lateral opening in said bore, a conveyor for chips extending upwardly from the cutter and operative to move the chips upwardly along the shank for discharge through said opening when the bit is rotated in one direction, and means operable by rotation of the bit in the same direction to feed material downwardly along the shank away from that portion of the bore which extends above the lateral opening in the chisel.

6. In combination with a mortising chisel an auger bit mounted for rotation within a bore in the chisel, said chisel having a lateral opening in said bore, a conveyor for chips extending upwardly from the cutter and operative to move the chips upwardly along the shank for discharge through said opening when the bit is rotated in one direction, and means operable by rotation of the bit in the same direction and cooperating with the bore of the chisel to oppose movement of material upwardly along the shank within the bore above the said lateral opening.

7. In combination, a mortising chisel and an auger bit mounted for rotation within a bore in the chisel, said chisel having a lateral opening in said bore, the bit having a conveyor groove extending upwardly from its cutter and operative to move the chips upwardly along the shank when the bit is rotated in one direction, and one of said parts having a conveyor groove disposed above the first mentioned groove and operable by rotation of the bit in the same direction to feed material downwardly along the bit.

8. In an auger bit having a shank with a cutter at the end of the shank, a conveyor for chips extending upwardly from the cutter and operative to move the chips upwardly along the shank when the bit is rotated in one direction, said conveyor including a discharge outlet at its upper portion, and means extending along a portion of the shank above said conveyor operable by rotation of the bit in the same direction to feed material downwardly toward the discharge outlet.
